J. C. VEIL.
HEATING AND VENTILATING SYSTEM.
APPLICATION FILED SEPT. 12, 1916.

1,331,404.

Patented Feb. 17, 1920.

FIG. 2

1952
Jules C. Veil
Frederick Gammie
Elsie E. Gammie
INVEN

INVENTOR

UNITED STATES PATENT OFFICE.

JULES C. VEIL, OF WEEHAWKEN, NEW JERSEY.

HEATING AND VENTILATING SYSTEM.

1,331,404.

Specification of Letters Patent.

Patented Feb. 17, 1920.

Application filed September 12, 1916. Serial No. 119,797.

To all whom it may concern:

Be it known that I, JULES CHARLES VEIL, a citizen of the United States, and residing at No. 9 Hudson Place, Weehawken, New Jersey, have invented new and useful Improvements in Heating and Ventilating Systems, of which the following is a specification.

My invention relates to improved means for heating, ventilating and cooling interior spaces in buildings, ships and other structures, together with improved means whereby heating, ventilating and cooling may be accomplished in a superior and simpler manner and with less operating expense.

I carry out my invention as hereafter described and claimed and illustrated, in the accompanying drawings, in which:

Figure (1) is a view partly in section and partly in elevation, illustrating features of my invention.

Fig. (2) illustrates a modification of my invention.

Similar numerals of reference indicate corresponding parts in all of the figures of the drawings.

The invention herein set forth is an improvement of certain features heretofore embodied in an application filed November 20, 1907, Serial No. 403045, allowed January 18, 1910, Patent No. 946889.

I am aware that, prior to my invention, heating and cooling systems have been installed in which water and other mediums are circulated by means of pumps. Also that air washers are made in which the spray water is first heated before it goes into the air washer. I, therefore, do not claim as new any of the above in my invention.

(1) is a pump operated by an electric motor (7). If electricity is not used, any other form of motive power can be used.

(6) is a heater for the purpose of heating the water circulated in the system to the desired temperature. Any of the present forms of hot water heaters can be used. If it is desired to cool the water instead of heating the same, any suitable refrigerating device can be used instead of the heater above described.

(26) is an indirect radiator, or other suitable form of radiator, and is used for the purpose of heating or cooling the air before

it goes to the rooms to be heated or cooled. Any of the present form of radiators or pipe coils can be used.

(20) is a motor operating fan (21). This motor is operated by the water, or other medium, which circulates in the system.

(27) is an air washer provided with two sets of spray chambers (27^a) and (27^b). Spray chamber (27^a) is connected to the pressure side of the system, while spray chamber (27^b) is connected to the discharge pipe of water motor (20). Any of the present makes of air washers can be used with my system. In using the terms air washer and spray chamber I wish it understood that this means any apparatus which heats, cools or humidifies air by means of liquids coming in direct contact with the air.

(31) is a return tank. This tank is connected to the main return line of the system. Tank is provided with a water supply from water main of building and also provided with a vent pipe for the purpose of getting rid of the air in the system. Tank may, or may not be used as desired. The system normally operates with the tank. If, however, it is desired not to use the tank, valves (18^a) and (18^b) are closed and valve (17^a) is opened.

The operation of my system is as follows:

Water, or any other suitable medium, is circulated by means of pump (1) through pipes (2) and (3) to heaters or coolers (6) where the water is heated or cooled to the desired degree. From there the water goes through pipes (5), (8) and (9) to indirect radiator (26). From indirect radiator (26) the water goes through pipes (10), (10^a), and (10^b) to water motor (20). This water motor operates fan (21). From this water motor the water goes through pipe (12) to spray chamber (27^b). From this spray chamber the water is led to tank (31) by means of pipes (13), (15) and (16). From tank there is a suction connection (18) to pump (1). When the water motor (20) is in operation it operates the fan at a high rate of speed which, in turn, causes a flow of air from air intake (28) through air washer (27). From the air washer the air goes through the fan (21) which, in turn, blows the air through the indirect radiator

(26) where the air is heated or cooled to the desired degree. From this indirect radiator (26) the air is blown through flues (29) which connect to the rooms which are to be heated or cooled.

As it is desirable to vary the temperature and humidity of the air which is blown into the rooms by the fan, the operation of the system can be modified in the following manner:

In case it is desired to have more water for air washing than is obtained from the discharge of water motor (20), the air washer (27^a) is put in operation by opening valve (11^a).

The system is so arranged that radiator (26) can be omitted and the water fed directly to water motor (20). This is accomplished by closing valves (9^a) and (9^b) and opening valve (14).

The system is also arranged so that air washer (27^b) can be omitted. In this case the water from discharge pipe of water motor (20) is led directly to tank (31) without going first through air washer (27^b). This is accomplished by opening valve (14^b) and closing valve (12^a).

On certain days it may be necessary, on account of atmospheric conditions, not to use the fan. In this case the water motor is shut off by closing valve (14^a), and valve (11^a) is opened which puts air washer (27^a) in commission. In this latter arrangement the water leaves the pumping device and from there it goes through radiator (26) and from there it goes through air washer (27^a) and then again to pumping device (1).

In the latter arrangement it is also possible to arrange the system so that an electric motor can be used to operate fan (21). The system, using an electric motor, is more fully shown in Fig. (2) of drawing. In this drawing (20^a) is a motor operated by electricity.

On certain days, on account of atmospheric conditions, it may be desirable not to use the heater or cooler (6). In this case it is put out of commission by closing valves (3^a) and (4^a) and opening valve (4^b).

Instead of taking the fresh air from the outside of the building, as shown on drawing, it can be arranged to take the air from within the building.

The liquid which goes through the air washer will heat and cool the air to a greater or lesser extent depending on the temperature of the liquid.

The motive power of the pump can be steam, gas, or electricity. When a steam pump is used the exhaust steam from same can be used for the purpose of heating the liquid which circulates through the system.

The dampers in the air connections of the system can be so arranged that they will open and close by the hydraulic pressure

which is maintained on the system. The valves on the pipe lines can be operated in a similar manner.

When the system is in operation the active circulation obtained in the main flow pipe (8) also causes a rapid circulation in the direct radiator (19).

In the drawings submitted with these specifications I only show one air washer, one indirect radiator, and one fan outfit. I wish it understood, in the actual installation of my system, any number of air washers, indirect radiators, or fan outfits can be used.

I do not desire to be understood as limiting myself to the specific construction shown and described further than as specified in the claims, as it will be apparent that the construction might be modified and changed in many ways without departing from the spirit and scope of my invention.

What I claim as new and desire to secure by Letters Patent is:

1. In a ventilating system, a temperature changing device, a radiator connected therewith, a motor driven fan, said motor being operated by the discharge from said radiator, a spraying means connected with the discharge from said motor, and a circulating air chamber arranged to carry the air, in contact with the spraying means where the air is washed and the temperature of said air is changed, through the fan and in contact with the radiator.

2. In a ventilating system the combination of a temperature changing device, a radiator connected therewith, a spraying device to receive the discharge from said radiator, a reservoir to receive the discharge from said spraying device, and a circulating pump connecting said reservoir to the temperature changing device to secure circulation of a liquid therethrough.

3. In a ventilating system, the combination of a temperature changing device, a feed pump connected therewith, an air circulating chamber, means in said chamber for changing the condition and temperature of the air passing therethrough, said means including a radiator connected with said temperature changing device, and a spray device connected with said radiator whereby the air is cleaned, moistened and given the desired temperature.

4. In a ventilating system, the combination of a temperature changing device, a feed pump connected therewith, an air circulating chamber, means in said chamber for changing the condition and temperature of the air passing therethrough, said means including a radiator connected with said temperature changing device, a spray device connected with said radiator whereby the air is cleaned, moistened and given the desired temperature, and a motor driven fan operated by the discharge from said radiator to

induce circulation of air through said air circulating chamber.

5. In a ventilating system a temperature changing device, a pump connected therewith, a radiator, a spraying device, and an air chamber arranged to conduct air in contact with the spraying device and the radiator, a motor driven fan adapted to be operated by the discharge from said radiator to induce the circulation of air through said air chamber whereby the air is cleaned and the temperature and humidity of the air is controlled.

6. In a ventilating system, a temperature changing device, a radiator connected therewith, a spraying means connected with said radiator to receive the discharge therefrom and an air circulating chamber arranged to carry the air in contact with the discharge from said spraying means and said radiator, whereby the temperature of the air is controlled and the air is purified and humidified.

7. In a ventilating system, a temperature changing device, a radiator connected therewith, an air washer connected with said

radiator to receive the discharge therefrom and an air chamber arranged to conduct the air through the air washer and in contact with the radiator whereby the temperature humidity and purity of the air is controlled, and a motor driven fan for inducing circulation of the air through said air chamber.

8. In a ventilating system, a temperature changing device, a radiator connected therewith, an air washer connected with said radiator to receive the discharge therefrom and an air chamber arranged to conduct the air through the air washer and in contact with the radiator whereby the temperature humidity and purity of the air is controlled, and a motor driven fan for inducing circulation of the air through said air chamber, a tank in said air chamber to receive the discharge from the air washer and a return connection connecting said tank with the temperature changing device.

JULES C. VEIL.
